Orville C. Mann,

UNITED STATES PATENT OFFICE.

ORVILLE C. MANN, OF OAK PARK, ILLINOIS.

VENTILATOR.

1,293,497.

Specification of Letters Patent.

Patented Feb. 4, 1919.

Application filed September 8, 1914. Serial No. 860,530.

To all whom it may concern:

Be it known that I, ORVILLE C. MANN, a citizen of the United States, residing at Oak Park, in the county of Cook and State of Illinois, have invented new and useful Improvements in Ventilators, of which the following is a specification, reference being had to the accompanying drawings, forming a part thereof.

10 The purpose of this invention is to provide an improved construction appurtenant to a window or window casing for affording ventilation of the apartment served by the window. It consists of the elements and features of construction shown and described, as indicated in the claims.

In the drawings:

Figure 1 is a vertical section through a window casing and a portion of the adjacent wall in which it is located, embodying this invention.

Fig. 2 is a section similar to Fig. 1, showing the parts concerned in the ventilation at open position.

25 Fig. 3 is a vertical section through the wall adjacent to the window casing, showing the latter in side elevation, with ventilating devices open.

In the structure shown in the drawings A represents the wall of the building in which the window casing, B, is situated. The window casing comprises the essential members of such a structure including the uprights, 1, 1, having the runways for the sash, 2 and 3, the bottom sill, 4, sloping down outwardly for drainage, and having at the inner side of the lower sash the customary bottom stop, 5, outside of which said lower sash is shut in the usual manner. For the specific purposes 40 of the present invention the uprights, 1, 1, are extended down below the bottom sill, 4, and from the level of the upper surface of said sill, there are extended inward and downward the said extensions, 1^a, forming 45 the ends of the ventilator box, which is thereby located under the sill and inward therefrom, extending out into the room a few inches but not more than is frequently customary to extend the inner sill of the window. The ventilator box is provided with a 50 bottom 5, slightly inclined down outwardly, and an inner side, 6, which extends upwardly from the inner edge of the slant bottom with a slight inward inclination. The 55 ventilator box is open at the upper side inside the window casing, and is provided

with a cover, 7, hinged to the inner side of said ventilator box for folding from a horizontal position which closes the box, up inwardly with respect to the room, to a position at which it has substantially the upward and inward inclination of the inner side of the ventilator box. At the outer side the ventilator box is open except as closed by the means hereinafter described, which 60 means are of the nature of coöoperating valves located entirely within the box. The outer opening of the box is preferably provided with a fine wire screen, 8, for excluding dust and insects and which may be applied in the same manner as any exterior window screen. The valve closures for the box above mentioned comprise a valve plate, 10, hinged to the upper side of the box, substantially in the vertical plane of the lower 75 sash (though the exact position is not material), and operated by links, 12, 12, connected to the inner side at or near lower edge and extending thence to the cover, 7, to which they are pivoted by means of brackets, 13, 13, which are proportioned so as to locate the pivotal connections of the links at a suitable distance below the lower surface of said cover to give said valve plate, 10, the desired range of movement from closed to 80 open position in and by the whole movement of the cover from its horizontal closed position to its upwardly and inwardly inclined position described. The proper location for the several connections of these links to the 85 valve plate and to the cover respectively will be readily ascertained by the mechanic in constructing the device in any given dimensions, that is, with a given size of window and any desired depth of ventilator box and 90 width of cover or sill. In order that the valve device may be adapted when closed to effectively exclude the elements, the valve plate, 10, mentioned, is not relied upon alone to effect the closure, but there is associated 95 with it a coöoperating valve member, 15, which is pivoted to the ends of the ventilator box at a very short distance above the outwardly inclined bottom of the box and which has its lower edge beveled at 15^a to make an 100 accurate and desirably water-tight seating upon the bottom of the box when said member, 15, is tilted up to a certain inclined position shown in Fig. 1, that position being 105 such that it will effectively shed water and prevent it even when driven by the wind from being driven up over the upper edge of 110

2
 said valve member. The said beveled edge, 15^a, of the valve member, 15, merges at the inner side of the valve in a cylindricoidal form or ridge, 15^c, which extends along the entire 5 length of said valve member, being curved about the pivotal axis of said member for about thirty degrees which is the intended range of swing of said valve member, 15, and thence the inner surface of said member extends substantially at a tangent to the said cylindricoidal boss. This construction adapts 10 the said valve member to rock to an angle of not exceeding 30 degrees from a position at which the said beveled edge seats closely 15 upon the surface of the bottom of the ventilator box, to a position at which said valve member stands inclined at an angle of about 45 degrees trending up inwardly, and in position to have its inner and upper edge 20 countered by the valve plate, 10, as the latter swings down outwardly from open toward closed position, said closed position being approximately vertical. The result of this construction is that as said valve plate, 25 10, is swung by the closing of the cover, 7, from open toward closed position its lower marginal portion engages the inner upper edge of the valve member 15, and swings the latter up toward closed position carrying its 30 beveled edge down to seating position described on the bottom of the box. In the absence of any provision to the contrary, the construction as thus far described, would be adapted to permit rain driven against the 35 valve plate, 10, to drip down behind the valve member, 15, into the box. This is prevented by a lip, 16, formed integrally with and projecting outwardly from the outer surface of the valve plate, 10, at a position 40 to overhang and admit behind it the upper inner edge of the valve member, 15, as the latter is swung up by the encounter with it of the lower marginal portion of the valve plate, 10, in the closing movement of the latter. This construction results in a shingling 45 relation of the two parts, 10 and 15, effectively excluding wind-driven rain.

The purpose of making the inner side of the box and the cover at open position upwardly and inwardly inclined as described, 50 is to direct the current of incoming air upwardly and inwardly into the room. This purpose is facilitated by providing means for closing the ends of the channel by which 55 air is thus directed. In order to provide such end closures without disfigurement of the structure which protrudes into the room, and in view of the fact that the cover, in order to reach the upwardly and inwardly 60 inclined position described, must swing through an arc of more than 90 degrees, I make such closure at each end by means of two sectoral members, 18 and 19, the first secured at one radial edge to the edge of 65 the cover, 7, and the second secured pivot-

ally to the cover, substantially at the center of the first sector which is in the axis of the hinge action for closing the box. The angular extent of the first sector, 18, is such that as the cover is closed and the sector is swung 70 down outside the ends of the box, said sector does not swing inward or forward past the inner side of the box, but is completely lapped upon the end of the box. The sectoral member, 19, is of sufficient radial angular extent to supplement the member, 18, for spanning the entire angle between the upper edge of the box and the cover at its most widely open position. Either of the two sectoral members may be engaged with 80 the other at their periphery by an inturned clip. As illustrated, the member, 18, being of the greater sectoral extent, is provided with such lip, 18^a, engaging the curved edge 85 of the member, 19. To cause the two members to be relatively extended as the cover is opened, a lug, 20, is provided on the lower inner edge of the sectoral member, 19, which encounters a stop on the side of the casing in the opening movement of the cover, and holds it while in the continuation of that opening movement, the sectoral member, 18, is withdrawn from its lap upon the member, 19, for extending the end closure as desired 90 to the full extent of the opening. A stop, 22, on the end of the box encountered by the edge of the member, 19, in the closing movement of the cover arrests it to cause the two members to be interlapped as the cover closes. In order to prevent the sectoral closing end device from being accidentally sprung outward when at open position, the stop, 21, is preferably in the form of a hook 95 which engages the lug, 20, and is encountered by it.

Since in closing the cover, 7, the sectors, 18 and 19, will enter the wall close alongside the ends of the box to the depths of the window recess, and since this prevents finishing the plaster snugly up to the casing at these ends for the distance occupied by the sectors, it is desirable to provide a pocket casing to receive the sectors so that around such casing the plaster may be properly tucked to 100 make the necessary weather-tight joints. For this purpose a casing, 23, is provided which may be made of sheet metal having flanges, 23^a and 23^b, at its upper and lower ends, respectively, by which it may be secured on the outer side of the end of the box 105 as shown. A proper weather joint may be made at the back or outer edge of the casing by tucking the plaster through from the forward or inner open end of the casing, and around the casing the plaster will be set 110 120 at any window casing.

I claim:—

1. In a ventilating device for window casings, in combination with the casing, a box forming a passage under the bottom sill 130

- of the casing leading from the outer to the inner side and opening at the inner side upwardly substantially at the level of the inner window-sill; a closure for said opening hinged to the inner side of the box for swinging toward the window toward horizontal position for effecting such closure; a link which is pivotally connected to the said cover at the under side thereof, and a member to which the end of said link is pivotally connected pivoted under the upper side of the box for swinging up inwardly against said upper side, said parts being proportioned and having their respective 10 pivots located to cause said member to reach and be stopped against the under side of the top of the box when the closure or cover is at open position inclined upwardly away from the window.
- 20 2. In a ventilating device for window casings, in combination with the casing, a box forming a passage under the bottom sill of the casing leading from the outer to the inner side of the window; a closure or cover 25 for the passage at the inner end, hinged to the inner side of the box for swinging toward the window and toward horizontal position for closing, and upward away from the window to an inwardly and upwardly- 30 inclined position for opening; a closure for the outer end of said passage hinged to the under side of the upper wall of the box for swinging upwardly and inwardly against said upper wall for opening, and a link 35 connecting said inner cover and said outer closure having its pivotal connection with the said inner cover offset from the inner or lower side thereof so as to be below a line connecting the hinge pivot of said cover 40 with the pivot of the link to the outer closure at closed position of said cover and closure, whereby the closing of said cover stops the outer closure against opening from the exterior.
- 45 3. A closure for a ventilating passage, comprising an upper member hinged at its upper edge and swinging up inward for opening and down outward for closing, and a lower member hinged at its lower edge 50 and swinging up outward for closing, and means stopping its opening movement while it trends up inwardly into the path of the downward swing of the upper member, whereby it is adapted to be engaged by the 55 latter and carried with it to closing position.
4. A closure for a ventilating passage comprising an upper member hinged at its upper edge and swinging up inward for 60 opening and down outward for closing, and a lower member hinged at its lower edge and swinging up outward for closing, and means stopping its opening movement at a 65 position at which it trends up inwardly into the path of the downward swing of the up-
- per member, whereby it is adapted to be engaged by the latter and carried with it to closing position, said upper member having on its outer side a downwardly and outwardly projecting lip positioned for encounter of the lower member in the end of the closing movement.
5. In a ventilating device, comprising a casing which forms a passage from the outer to the inner side of a wall, in combination 70 with such casing, a closure for the inner end of the passage consisting of a member hinged for swinging inwardly to open and having sectoral end pieces which swing edge-wise into the wall for closing, and pocket 75 members secured to the outer side of the ends of the casing opening upwardly to receive the sectors in the closing movement.
6. In a ventilating device for a wall, a boxing forming a passage through the wall 80 from outer to inner side, and opening upwardly at the inner side of the wall; a hinged cover for the inner end of the passage, and a hinged closure for the outer end 85 of the passage; a connection from the cover to the closure for simultaneous opening and closing movements of said cover and closure, the cover being hinged for swinging, in fully 90 opening past a vertical position above its hinge pivot; whereby at that position it tends by gravity to hold the closure in open position.
7. In a ventilating device for a wall, a boxing forming a passage through the wall 95 from outer to inner side, and opening upwardly at the inner side of the wall; a hinged cover for the inner end of the passage, and a hinged closure for the outer end 100 of the passage; a connection from the cover to the closure for simultaneous opening and closing movements of said cover and closure, the cover being hinged for opening upwardly and for swinging in full opening 105 past a vertical plane through its hinge pivot to reach its fully open position, and means 110 for stopping the opening movement of the closure, whereby the opening movement of the cover is stopped after it has passed said vertical position; the connection between the cover and closure being adapted for pushing as well as pulling, whereby the cover 115 tends to close the closure when said cover is swung past said vertical position in its own closing movement.
8. In a ventilating device for a wall, a 120 boxing forming a passage through the wall from inner to outer side, said passage opening upwardly at the inner side of the wall; a cover for the inner end of the passage hinged to the boxing at the edge of said 125 cover remote from the wall, and adapted to open by swinging about its hinge upwardly and away from the wall; a rigid member connecting the cover and closure pivoted to said parts at their proximate sides, the pivot 130

of said connecting member to the cover being offset below the lower side of said cover at its closed position past the plane containing the pivot of said connection to the closure and the hinge axis of the cover; whereby opening movement of the closure is resisted by, and tends to hold tightly closed, the cover.

9. In a ventilating device for a wall, a
10 boxing forming a passage through the wall from inner to outer side thereof, opening upwardly at the inner end; an upwardly-opening cover for said inner end; a closure for the outer end comprising two members
15 one hinged at the upper side and the other hinged at the lower side of the passage and

engaging each other at closed position, the member which is hinged at the upper side being extended down past the upper edge of the other member at the inner side thereof 20 at closed position of said members, and a link connecting said closure member which is hinged at the upper side to the cover which closes the inner end of the passage.

In testimony whereof, I have hereunto set 25 my hand at Chicago, Illinois, this 31st day of August, 1914.

ORVILLE C. MANN.
